REFRIGERATING CONSTRUCTION

Frederick H. Hibberd, Bayside, N. Y., George H. Woodard, Phillipsburg, N. J., and John Kirgan, Easton, Pa., assignors to Ingersoll-Rand Company, Jersey City, N. J., a corporation of New Jersey

Application March 23, 1934, Serial No. 716,946

8 Claims. (Cl. 62—152)

Our invention relates to improvements in refrigerating constructions, and more particularly to a novel type of evaporator in which a portion of a liquid refrigerating agent or medium, such as water, is vaporized to lower the temperature of said medium.

The evaporator of this invention comprises multiple chambers as disclosed in the application of Frederick H. Hibberd, Serial No. 716,947, filed even date herewith, for patent on a Refrigerating construction. An object thereof is to provide an evaporator including a plurality of compartments or chambers having therein either longitudinal or transverse weirs at the tops of which, or adjacent thereto, the vaporization of a portion of the refrigerating medium is accomplished; each weir forming in conjunction with a part of the interior of the chamber containing it a space or well to which the refrigerating medium is supplied, and which is adapted to prevent further inflow of said liquid refrigerant whenever said chamber is cut out of the system and thus rendered inoperative.

A further object of our invention is to provide a refrigerating system having multiple evaporator chambers, with a conduit to supply the refrigerant to said chambers, said conduit having a valve therein exterior to said evaporator, and one of said chambers containing a regulator member connected to said valve and arranged to maintain the refrigerant, after being chilled by vaporization of a portion thereof, at a constant level in said chambers, independent of the rate of outflow therefrom.

The objects and advantages of the invention are clearly set forth in the ensuing description, which presents several forms in which our invention is embodied. The disclosure, however, is illustrative only, and numerous alterations can be made without going beyond the principle of the invention, or exceeding the spirit and scope of same.

In the drawings, Figure 1 shows an outline of a refrigerating system according to our invention, partly in section,

Figures 2 and 3 are horizontal sections on lines 2—2 and 3—3 respectively in Figure 1,

Figure 4 is a similar view showing a slightly modified construction,

Figure 5 is a view similar to Figure 1 showing another embodiment of the invention, and

Figure 6 is a transverse section on the line 6—6 of Figure 5.

In the drawings the same numerals identify the same part throughout.

Referring first to Figure 1, we show at 1 an evaporator having a supply pipe 2 and an exhaust or delivery pipe 3, water being admitted to the evaporator 1 and after being cooled therein being withdrawn through the conduit 3 and carried off to be used as intended. The evaporator 1 contains several compartments or chambers 4, 5, 6 and 7 separated from one another by means of transverse partitions 8. A portion of the incoming water is vaporized in one or more of these chambers, and the water vapor is removed by means of suitable evacuator members, such as steam ejectors or steam jet boosters, which are at the tops of the chambers and discharge into a steam exhaust pipe 9. These ejectors in operation maintain the vacuum high enough in the chambers to cause vaporization of part of the water.

All of the water vapor formed in the chambers of the evaporator is transmitted through the pipe 9 to a suitable condenser (not shown) to be liquefied. The steam ejectors raise the pressure of the water vapor to the pressure in the condenser, which is somewhat higher than that in the chambers which are working. The ejectors are supplied from a common steam line 10.

The water supply pipe 2 has branches 11 leading to the supply chambers 5, 6 and 7, and a smaller branch pipe 12 which enters the compartment 4. The inlet openings through which water enters the evaporator by way of the branches 11 are indicated at 13. The common delivery pipe or header 3 communicates with the lower ends of all the chambers through branches or riser pipes 14 by way of outlet openings 15. The communication between the conduit 3 and any of the chambers of the evaporator is always free because no valves are employed in either the delivery pipe 3 or any of the branches 14. So long as the various chambers are in operation and water is vaporized therein and water vapor removed therefrom, the water in the various chambers will be cooled to the required extent. If, however, one of the compartments is not operating, the level of the liquid contents or the cooled water therein will automatically sink, for the chilled contents of this particular chamber will be forced out, because the pressure then rises in that chamber until it equals the pressure in the condenser, but enough of the water will be trapped in the riser connected to that chamber to seal it and keep it from communicating with the other chambers. As this method is fully set forth in the application of Frederick H. Hibberd, Serial No. 716,945, for patent on Controlling devices,

filed of even date herewith, that part of the apparatus herein described which gives this mode of action is therefore not recited in the claims appended hereto.

5 When one of the boosters is turned off for purposes of saving steam at reduced load, and condenser pressure is exerted in the corresponding evaporator chamber, the water to be chilled must be prevented from entering this inactive chamber.
10 This is necessary because the inactive chamber is now in free communication with the condenser and if relatively cold water enters the chamber it will become heated by the condensing therein of the discharge steam from the boosters present in the condenser. Part or
15 all of the desired refrigerating effect will therefore be lost. Hence the interior of each of the chambers 5, 6 and 7 is provided with a weir 16 adjacent one side of the chamber which may extend longitudinally between the partitions 8 and one of these and the end of the evaporator 11. Each weir rises from the bottom of the evaporator and extends toward the top. Adjacent the upper edge the weirs may be pierced with a
20 row of openings 17. Each of the weirs together with the adjacent portions of the interior of each chamber 5, 6 or 7 provides a space or well 18 to which the water is admitted through the inlet 13, and a certain portion thereof will be vaporized
25 at once as it is delivered from the wells into the chambers. The top of pipe 12 may have openings similar to openings 17 in the weirs 16, at the same level.

To carry away the water vapor, each of the chambers 4, 5, 6 and 7 has an outlet 19 in the top leading to steam ejectors or steam jet boosters 20. These are in the form of L-shaped tubular members which communicate at one end with the outlets 19 and are connected at their opposite ends to the conduit in which they discharge. Each ejector receives a steam nozzle 21 connected by pipes 22 to the steam line 10, and each branch pipe carries an admission and shut-off valve 23. The ejectors for all the chambers discharge into the conduit 9 leading to the condenser (not shown), but the ejector for the chamber 4 is of much smaller size and capacity than the others, and serves a special purpose described below. The chamber 4 is not provided with a weir but the inlet pipe 12 extends from the bottom as high as any of the weirs 16 in the other chambers, and forms a well in effect. All of the weirs and the pipe 12, are of the same height.

Water to be cooled may enter all the chambers through the branches 11 and the inlet pipe 12, and as part of it is vaporized the water vapor is removed by the steam ejectors through the pipe 9. The water which is chilled by the vaporization of part thereof, passes out through the risers 14 and the delivery conduit 3 as above set forth. So long as the steam jets are supplied from the line 10 the vacuum in the chambers remains high enough, but if any one of the steam jets is shut off the absolute pressure in the chamber to which that jet is connected, will increase and become equal to the pressure in the condenser. This pressure will lower the level of the water in the well below the top of the weir or openings 17 in that chamber, so that no more water can enter the chamber that is not being evacuated. This condition is shown in Figure 4. The remaining chambers will continue in operation and discharge the chilled refrigerant through the common delivery conduit 3. The condenser pressure in the 75 chamber which is out of operation will force down

the level of the water therein and thus compel the conduit 3 to drain that chamber to a point which will be generally in the riser 14 below the outlet opening 15. The risers, however, will be high enough so that some of the water will be trapped in the riser connected to the inoperative chamber, and seal the same from below, and the higher pressure therein will be prevented from taking effect in any of the other chambers. See the chamber 7 in Figure 1.

10 The system will be operated by including all the chambers or by cutting out one or more of the chambers 5, 6 and 7. Chamber 4 must always be in operation because it contains a float 29 which actuates a valve 26 in the water supply line 15 2 outside of the evaporator. This valve is shown as a rotary valve having an outside arm 27 connected by a rod 28 which passes through the wall of the chamber 4, to the interior thereof and is connected to a bell crank lever which supports 20 the regulating element or float 29. This float so actuates the valve 26 that the water is maintained at a constant level in the chambers of the evaporator independent of the rate of outflow. If this water level drops the valve is opened further 25 and if the water level tends to rise it is moved towards closed position. The steam jet for the chamber 4 which discharges into the pipe 9, while somewhat smaller than the other steam jets, will be so proportioned that it will maintain the same 30 vacuum in this chamber as in the other chambers which are working.

35 This is insured by admitting a small amount of water through the small conduit 12 thereby establishing the temperature and pressure in chamber 4 as substantially the same as that in the other active chambers.

40 It should be noted that the pipe 12 and the booster for the chamber 4 are of such relatively small capacity that no appreciable refrigerating effect is produced and the sole function of this booster and its chamber 4 is to maintain the proper water level in the active chambers irrespective of which ones are in use, and without necessitating manipulation of any float control 45 valves for putting any of the chambers into or out of service. With all the chambers in communication with one another through the risers 14, the chilled water therein tends to seek the same level in the chambers that are working because each chamber is subjected to the pressure head of the cooled water in the other chambers, and this level will be constant so long as the vacuum maintained by the steam jets is the same in the chambers which are working. When any 55 chamber is cut out of operation the admission of further water thereto from the pipe 2 is prevented because the higher condenser pressure in that chamber forces the level of the inflowing water down from the top in the well, while the 60 water already chilled in that particular chamber is forced out and that chamber is emptied except for a portion which remains in the riser pipe, at the level indicated in the riser 14 of the chamber 7, for example, in Figure 1, to seal this chamber. The pump 30 in the line of the conduit 3 insures the transmission of the cooled water to the place of use.

65 In Figure 2 the top of the well 18 is shown as 70 uncovered. In Figure 4, however, this space is provided with a closure 31, and the water is discharged through the openings.

75 Figures 5 and 6 show a similar construction but with weirs 16' arranged transversely par-

allel to the partitions 8, and the steam ejector of chamber 4 is of the same capacity as the other ejectors. This chamber has a weir 16' like the other chambers, instead of an inlet pipe 12, the 5 operation of this construction is the same as described above, but the design is somewhat simplified and costs less to build.

The provision of weirs in a broad sense is not a part of our invention. Likewise, the idea of 10 the chamber 4 with a small inlet pipe 12 and the control connection for the pipe 2 is not broadly speaking a part of this invention, for these features are recited in the claims of the application of Frederick H. Hibberd for patent on Refrigerating apparatus, Serial No. 716,947, filed of even date herewith. We do, however, claim the idea of 15 the particular arrangement of weirs in longitudinal and transverse directions and the position of the valve 26 in the pipe 2 outside of 20 the chamber 4 in this application.

It will be seen that, as illustrated in Figure 2, the level of the inflowing water in any chamber which is operating is higher than the level of the chilled water at the bottom of the chamber, 25 where it collects before passing out through the risers 14. Vaporization of part of the water takes place as the incoming water flows downward from the upper portions of the wells 18 and the pipe 12. As long as the water vapor is sufficiently 30 evacuated from any chamber by the members 20, the level of the incoming water remains high enough to be discharged from the well. When the vacuum is lessened upon the stoppage of any 35 one of the steam jet boosters the increase of absolute pressure within the chamber which is put out of operation forces down the level of the incoming water in the wells so that no more inflow of water occurs and at the same time it depresses the level of the chilled water therein 40 to the point indicated in connection with the riser 14 connected to the chamber 1.

We claim:

1. A refrigerating construction comprising an evaporator to receive a liquid refrigerant, said 45 evaporator containing a plurality of chambers, a well in each of said chambers, means for admitting said liquid refrigerant to said wells to be discharged from the upper portions thereof in said chambers, said means containing a valve 50 outside of said evaporator, a regulating element in one of said chambers, connections between same and said valve to control the supply of said liquid refrigerant and render it independent of the rate of outflow of said chambers, a common 55 delivery pipe connected to said chambers and means for removing vaporized refrigerant from said chambers.

2. A refrigerating construction comprising an 60 evaporator containing a plurality of chambers, means for supplying a liquid refrigerant part of which is to be vaporized in said chambers, means for evacuating vaporized refrigerant from said chambers, means for delivering the remainder of the liquid refrigerant from said chambers, a valve 65 in the supply means on the outside of said evaporator, and a regulating element in one of said chambers connected to said valve arranged to maintain the liquid refrigerant in said chambers at a constant level.

3. A refrigerating construction comprising an 70 evaporator to receive a liquid refrigerant, said evaporator containing a plurality of chambers, a well in each of said chambers, means for admitting said liquid refrigerant to said wells to be

discharged from the upper portions thereof into said chambers, said means containing a valve outside of said evaporator, a regulating element in one of said chambers, connections between said valve and said element to control the inflow of 5 said liquid refrigerant, a common delivery pipe below said evaporator, branch risers connecting said delivery pipe to said chambers, and means for removing vaporized refrigerant from said chambers.

4. A refrigerating construction comprising an 10 evaporator containing a plurality of chambers, a longitudinally extending weir in each chamber, forming with a portion of the inside thereof a well to receive a liquid refrigerant, said well being closed at the top and having discharge openings in the side thereof, a supply pipe in free and independent communication with the lower portion of each of said wells to admit the liquid refrigerant thereto, means for delivering said liquid 15 refrigerant from said chambers, and means for evacuating vaporized refrigerant from said chambers, connected to maintain substantially equal vacua in said chambers.

5. A refrigerating construction comprising an 20 evaporator containing a plurality of chambers to receive a liquid refrigerant, a supply pipe having branch connections with said chambers, one of said connections extending above the bottom of one of said chambers and forming a well therein, means forming wells in the other chambers to the lower portions of which said pipe delivers, said supply pipe containing a valve outside of 25 said evaporator, a regulating element in the first named chamber, connections from said element 30 to the said valve to control the supply of said liquid refrigerant, a common delivery pipe connected to said chambers, and means for removing 35 vaporized refrigerant from said chambers.

6. A refrigerator construction comprising an 40 evaporator having a chamber, means for supplying to said chamber a liquid refrigerant, a portion 45 of which is to be vaporized therein, an evacuator member to remove vaporized refrigerant from said chamber, the evaporator containing a second chamber, a connection between the second chamber and said means, an evacuator member of relatively small capacity to remove vaporized refrigerant from the second chamber, common 50 delivery means connected to said chambers and a regulator member actuated by the level of the liquid in the second chamber and connected externally of said second chamber to control said 55 supply means.

7. A refrigerator construction comprising an 60 evaporator having a chamber, means forming with a part of the interior of said chamber a well having its upper portion above the bottom of the chamber, means for supplying to the well a liquid 65 refrigerant part of which is to be vaporized in said chamber, an evacuator for removing vaporized refrigerant from said chamber, the evaporator containing a second chamber, an inlet pipe for 70 said second chamber connected to said means, said pipe having its outlet end at substantially the same height as the upper portion of said well, an evacuator of relatively small capacity for the second chamber, common delivery means for said chambers, and a regulator element actuated by the refrigerant in the second chamber and connected externally of the second chamber to control the supply means.

8. A refrigerating construction comprising an 75 evaporator containing a plurality of chambers, a

longitudinally extending weir in each chamber forming with a portion of the inside thereof a well to receive a liquid refrigerant, said well being closed at the top and having discharge openings in the side thereof, a supply pipe connected in multiple with the lower portion of said wells to admit the refrigerant thereto, means for deliver-

ing said refrigerant from said chambers, and means for evacuating vaporized refrigerant from said chambers, connected to maintain substantially equal vacua in said chambers.
